UNITED STATES PATENT OFFICE.

EDWARD ALLAN THOMSON, OF FINCHLEY, LONDON, ENGLAND.

HEAT-INSULATION LINING FOR COLD-STORAGE CHAMBERS OR HOLDS USED FOR THE STORAGE OF REFRIGERATED PRODUCE.

Original application filed October 18, 1924, Serial No. 744,369, and in Great Britain August 8, 1925.

Divided and this application filed July 27, 1926. Serial No. 125,249.

This invention relates to heat insulation linings for cold storage chambers or holds for the storage of refrigerated produce and consists of an improvement in or modification of the heat insulation linings described and claimed in the specification of my pending application for Letters Patent Serial No. 744,369.

According to my present invention, means are provided for adjusting the wood grounds both parallel to the plane of the lining panels and in a direction perpendicular thereto, so as to facilitate the fitting of the wood grounds to existing beams, frame members and the like, which in practice are not arranged at a quite uniform distance apart and do not have their flanges lying quite uniformly in a common curved surface or envelope. For this purpose, the ground is made with an inner face or base which is adapted to rest against a correspondingly shaped surface on the beam, frame-member or the like itself or on a liner, bracket or chock secured to such beam, frame-member or the like, the ground being secured in position by means of a nut on a bolt or stud which extends through a hole in the ground and is secured to the beam, frame member or the like, or to the bracket, chock or liner thereon, so that by providing a suitable amount of clearance in the bolt- or stud-holes in the wood ground, or by varying the position of the bolts or brackets on the beams, frame members or the like, or of the studs in the chocks, the grounds may be adjusted laterally as required to enable the panels between the grounds to be made of a standard length and the grounds themselves to be made of a standard cross-section all prepared in the factory ready for erection. Moreover by introducing an individual liner of suitable thickness between the flange of the beam or frame-member and the inner face of the ground, or by employing chocks of suitable depth or thickness, the position of the outer face of the ground can be adjusted as desired. Furthermore the wood grounds can be drilled in the factory to the correct distance between the centres of the bolts or studs on the beams, frame-members, brackets or chocks, so that the bolts or studs can pass through the wood grounds without any fitting.

In order to reduce transfer of heat to the

cold chamber through metal beams or frame members, in cases where hanger bolts are employed, heat insulating liners may be arranged between the hanger bolt and the web of the beam or frame member, the bolt securing the hanger bolt to the web of the beam or frame-member extending through a hole in such liner.

In the accompanying drawings, I have shown how my said invention may be conveniently and advantageously carried into practice. In these drawings:—

Figures 1 and 2 are sectional elevations taken on planes at right angles to one another showing one form of my improved construction.

Figures 3, 4, 5 and 6 are corresponding views to Figure 1 showing further forms of my improved construction.

Figures 7 and 8 are corresponding views to Figures 1 and 2 respectively showing a still further form of construction.

Figure 9 is a similar view to Figure 1 showing still another form.

In the arrangement shown in Figures 1 and 2, A is the steel deck; B a supporting beam thereof; C granular insulating filling material; and D, D hanger bolts supported on the web of the beam B by bolts E.

The wood ground F is provided on one side with a groove G to receive one edge of a lining panel H, the other edge of which rests on the ledge J of a recess on the other side of the wood ground, and is secured therein by means of a capping strip K. The hanger bolts D are provided with nuts for supporting the wood grounds F, and their lower ends extend through and support by means of suitable nuts metal clips L, L for receiving brine pipes M, M and meat rails such as N.

The upper surfaces of the wood grounds F are made flat, so as to be adjustable laterally on the lower flanges of the beams B. The conduction of heat into the hanger bolts D, D is reduced by means of ferrules O, O and washers P, P and Q, Q of hard fibre, such as what is known as vulcanized fibre or indurated fibre. By using washers Q of different thicknesses, the position of the hanger bolt can be adjusted laterally as desired.

In the modification shown in Figure 3, a liner S is arranged between the lower flange

of the beam B and the flat upper face of the wood ground F.

In Figure 4, which is adapted for use as bulkhead insulation or side insulation, i. e. 5 insulation attached to the vertical frames at the sides of the vessel, the flat inner face of the wood ground F rests against a short wood chock T bolted to the side of the frame member V. The wood grounds F are here 10 secured to the chocks T by means of coach-screw studs W, the holes in the chocks being made as shown of sufficient diameter to permit a small amount of lateral adjustment of the grounds. Moreover the position of the 15 studs W in the chocks can be varied for the same purpose.

Figure 5 shows a similar construction to Figure 4, in which a liner Z of asbestos is 20 arranged between a bulb iron frame member 1 and a chock T. This construction may be used on bulkheads separating the refrigerating chamber from coal bunkers, in order to 25 isolate the wood work from the steel structure in the event of the latter becoming overheated, e. g. in cases where the coal on the other side takes fire.

Figure 6 shows a further arrangement in 30 which an extended chock T' is bolted to one side of an angle iron bulkhead stiffener 2, asbestos millboard washers 3 being arranged between the chock and the stiffener and the bulkhead 4.

The two constructions illustrated in Figures 5 and 6, in which asbestos millboard is 35 employed, are both adapted for use in forming a fireproof construction for a cold storage chamber. In these cases the insulating filling C is advantageously of slag wool.

In the construction shown in Figures 7 40 and 8, an angle iron bracket 5 is arranged against the web of the bulb iron frame member I and is provided on its flanges with elongated slots 6, 7 respectively. The slot 6 receives a bolt 8 whereby the bracket 5 is 45 adjustably secured to the web of the bulb iron frame, so as to permit of the wood ground F being adjusted perpendicularly to the plane of the panels. The slot 7 receives the bolt 9 that extends through the hole in the wood ground F and enables the wood ground 50 to be adjusted laterally, i. e. in the direction of the plane of the adjacent panels H, H.

In the construction shown in Figure 9, the 55 channel-iron frame-member B is provided with a slot 10 through which extends a bolt 11 that also extends through the hole in the wood ground F and thus enables the wood ground to be adjusted in the direction of the plane of the adjacent panels H, H.

In the constructions illustrated in Figures 60 7 to 9, the bolts 8, 9 and 11 and the bracket 5 can be provided with bushings and liners such as the bushings P, Q and S described with reference to Figure 3, so as to reduce the conduction of heat from the skin plating

or deck A' to the parts of the bolts 9, 11 in contact with the atmosphere in the cold storage chamber.

In cases where the web of the frame members of a vessel requires to be set at an angle other than 90 degrees to the inner surface of the heat insulation lining (i. e. in order to maintain the webs of such frames at right angles to the centre line of the vessel) for example, in positions close to the bow and stern where the outer surface of the vessel is curved, the angle of the face of the chock T or T', Figures 4, 5 and 6, against which the inner face or base of the wood ground F rests, can be varied to suit the alignment of the inner surface of the lining; or the face or faces of the chocks resting against the bulb iron, angle or other frame, or against a frame and plating, can be varied to correspond with the desired alignment of the inner surface of the lining. 70 75 80 85

In cases where the inner face or base of the wood ground rests against a slotted angle iron bracket or lug 5, such bracket or lug is 90 preferably made with its flanges or flange faces arranged at an angle greater than 90 degrees to each other in order to correspond to the desired alignment of the inner surface of the lining.

Moreover in cases where Z-section frames are employed, which are built up of two 95 100 105 110 115 120 125 130 135 140 145 150 155 160 165 170 175 180 185 190 195 198 200 202 204 206 208 210 212 214 porting the lining panels and with inner faces that are substantially parallel to the general adjacent exterior surface of the lining and rest against correspondingly shaped supports, said supports for the grounds, means for securing the grounds to the supports so as to permit adjustment of the grounds in a direction parallel to the general adjacent exterior surface of the lining, means for adjusting the grounds in a direction perpendicular to the general adjacent exterior surface of the lining, and means for securing the panels to the grounds so as to be individually detachable from the interior of the chamber in a direction substantially perpendicular to their own planes.

3. A heat insulation lining for cold storage chambers, said lining comprising lining panels, wood grounds extending beyond said lining panels into the interior space of the chamber and provided with surfaces for supporting the lining panels and with inner faces, that are substantially parallel to the general adjacent exterior surface of the lining and rest against correspondingly shaped surfaces on members secured to the main supports of the lining, said members, means for securing the grounds to said members, and means for securing the panels to the grounds so as to be individually detachable from the interior of the chamber in a direction substantially perpendicular to their own planes.

4. A heat insulation lining for cold stor-

age chambers, said lining comprising lining panels, wood grounds extending beyond said lining panels into the interior space of the chamber and provided with surfaces for supporting the lining panels and with inner faces that are substantially parallel to the general adjacent exterior surface of the lining and rest against correspondingly shaped surfaces on chocks, said chocks secured to constructional members of a ship, screwed members and nuts for securing the grounds to said chocks so as to permit adjustment of the grounds, and detachable strips for securing the lining panels to supporting surfaces on the grounds.

5. A heat insulation lining for cold storage chambers, said lining comprising lining panels, wood grounds extending beyond said lining panels into the interior space of the chamber and provided with surfaces for supporting the lining panels and with inner faces that are substantially parallel to the general adjacent exterior surface of the lining and rest against correspondingly shaped surfaces on wood chocks, said wood chocks secured to constructional members of a ship, screwed members and nuts for securing the grounds to the chocks, and detachable strips for securing one border of lining panels to abutment surfaces on the grounds, the opposite border of the panels resting in grooves in the corresponding sides of the grounds.

EDWARD ALLAN THOMSON.
